CLEMENT C. RICHARD, CLARENCE A. RICHARD, AND OTIS K. RICHARD, OF DETROIT,
MICHIGAN.

PUNCH AND DIE RETAINER.

REISSUED

1,393,040.

Specification of Letters Patent.

Patented Oct. 11, 1921.

Application filed November 19, 1919. Serial No. 339,136.

To all whom it may concern:

Be it known that we, CLEMENT C. RICHARD, CLARENCE A. RICHARD, and OTIS K. RICHARD, citizens of the United States, residing at 5 Detroit, county of Wayne, State of Michigan, have invented a certain new and useful Improvement in Punch and Die Retainers, and declare the following to be a full, clear, and exact description of the same, such as 10 will enable others skilled in the art to which it pertains to make and use the same, reference being had to the accompanying drawings, which form a part of this specification.

This invention relates to tool retainers and 15 the principal object of the invention is to provide a retainer means for the tool to prevent withdrawal thereof from the holder. The principal feature of the invention is involved in the provision of a retainer having 20 an aperture for the tool shank and an angularly positioned aperture opening into the said first named aperture and containing a spring pressed ball partially extending into the tool retaining aperture to bindingly engage the shank of the tool and prevent withdrawal of the tool from the retainer. A further feature of the invention is involved in the construction of the tool shank in which a 25 groove is formed to receive the ball, the groove in cross section having a radius equal to the radius of the ball and which when the ball is seated therein prevents rotation of the tool in relation to the retainer. An additional feature of the invention is involved in 30 the peculiar character of the ball receiving groove which groove is arcuate in a plane parallel to the longitudinal axis of the tool and also in a plane at a right angle thereto, the radius of the latter form being equal to 35 40 that of the ball whereby the tool is accurately positioned and held from rotative movement. Another feature of the invention resides in the provision of a punch and die retainer of the character above set forth in 45 which the ball retaining aperture for the punch is positioned at an angle to the longitudinal axis of the punch and the ball retaining aperture for the die is positioned at an angle substantially opposite to that of the 50 ball retaining aperture for the punch whereby the withdrawal movement of the punch from the die prevents the longitudinal movement of either tool in its holder and prevents the die from following the punch or 55 the punch from remaining in the die. These

and other objects and the several novel features of the invention are hereinafter more fully described and claimed and the preferred form of construction is shown in the accompanying drawings in which:—

Figure 1 is a section through a punch and die and retainers therefor illustrating the means for securing a punch or die in the respective retainer.

Fig. 2 is a section through the punch and retainer taken on line 2—2 of Fig. 1.

We have preferably shown in the drawing a tool retainer as used with a punch and die and as will be noted the retainer 1 is formed with an annular flange 2 at the upper end thereof which is secured against the punch plate 16 by means of a member 3 fitting over the said annular flange and encircling the retainer and secured to the punch plate 16 by fillister head screws 17 shown in Fig. 1. In this manner the retainer is secured to the punch plate and held from rotation and as will be noted the retainer 1 is centrally apertured to receive the punch shank. Within the wall of the said retainer is an angularly positioned aperture 4 in which a ball 5 is positioned. Adjacent the end of the aperture opposite the ball is provided an annular groove in which is positioned a spring washer 6 against which one end of the spring 7 engages the opposite end of the spring engaging against the ball 5 as shown. It is to be noted that the aperture 4 opens into the central aperture but that the opening between the two apertures is less than the diameter of the ball 5 thereby preventing the ball from passing out of the aperture 4 at the bottom. As will be noted from Fig. 1 the punch shank 8 is provided with a groove arcuate in a plane parallel with the longitudinal axis of the punch and also arcuate in a plane at a right angle to the aforesaid plane, the radius of the last named groove being equal to the radius of the ball 5. It can be seen more particularly from Fig. 2 that the ball 5 extends into the groove 9 in the punch shank and is tightly held in engagement therein by the spring 7, the opposite side of the ball at the same time engaging the angularly positioned wall of the aperture 4.

In the lower half of Fig. 1 is shown a die or die block 10 which is held in a retainer similar to that of the punch shank and this die block is provided with a groove 9^a similar to the groove 9 in the punch shank. The re-

tainer 1^a is also provided with an angularly positioned aperture 4^a in the wall thereof and a central aperture is provided therein to receive the die or die block 10. Within the 5 aperture 4^a is provided a spring washer 6^a against which one end of the spring 7^a engages, the opposite end of the said spring engaging the ball 5^a which device is similar to that shown in the upper half of Fig. 1, 10 being positioned at an opposite angle as shown. The spring 7^a in like manner forces the ball into the arcuate groove 9^a of the die or die block 10 and prevents the same from withdrawal from the retainer. The retainer 15 is also provided with an annular flange 2^a and a member 3^a is provided similar to the member 3 encircling the retainer and providing in combination therewith an additional wall support for the block which aids in preventing breakage of the die block from the 20 heavy blows delivered by the punch head.

The assembly of the device is as follows: The punch 8 is forced by the operator into the central aperture in the retainer 1 and 25 when positioned as shown in Fig. 1, the ball 5 engages in the groove 9 in the punch shank preventing the punch from rotation in relation to the retainer and attempted withdrawal of the punch from the retainer is 30 prevented by the binding action of the ball 5 between the angular wall of the aperture 4 and the wall of the arcuate groove 9 of the punch shank 8. It is to be noted that the end of the punch shank 8 engages against the 35 punch plate 11 against which the retainer is secured so that upward movement of the punch is prevented and by the use of the spring pressed ball engaging in the arcuate groove in the punch shank the punch is 40 locked in the retainer and is held immovable therein. This is also true of the die or die block 10, the said die being prevented from downward movement by the die plate 18 and 45 prevented from rotation or upward movement by the spring pressed ball 5^a engaging in the arcuate groove 9^a in the die block. In order to remove either the punch or die from the respective retainer, the operator may extend a rod or similar instrument through the 50 aperture 12 or 12^a in the flat face of either retainer and force the ball 5 or 5^a back into the aperture 4 or 4^a away from and out of the arcuate groove 9 or 9^a in the punch or die block respectively whereupon either the 55 punch or die block may be easily withdrawn from the respective retainer. It will be noted that the retainers are not limited to use with any certain type of tool but may be used in different types of punch presses, drill 60 presses and other machines where a tool must necessarily be held from rotation and at the same time from longitudinal movement in relation to the retainer or chuck within 65 which it is secured. In a machine where rotation of the tool is allowable the arcuate

groove may be dispensed with, the ball in this case only engaging the cylindrical face of the tool shank thereby preventing withdrawal of the tool from the retainer and at the same time allowing rotation thereof. It 70 is also to be noted that the groove 9 or 9^a in the tool need not necessarily be arcuate in a plane parallel to the longitudinal axis of the tool this form being shown on account of greater ease of manufacture, the necessary 75 characteristics of the groove being that the groove be arcuate in cross section on a radius equal to the radius of the ball so that when the ball is seated in the groove the tool is prevented from rotative movement. The 80 bottom of the groove may be parallel to the longitudinal axis of the tool or at an angle thereto or arcuate in form as shown, either form being adapted to be bindingly engaged by the spring pressed ball in the retainer 85 wall to prevent either rotation or longitudinal movement of the tool. This retainer may be also used with square shank tools and the arcuate groove dispensed with, the square shank fitting in a square aperture in the retainer thereby preventing rotation of the tool 90 in relation to the retainer and the ball engaging one of the flat faces of the shank thereby preventing withdrawal of the tool from the retainer. The retainer may be 95 made in different sizes with different central apertures as illustrated by the retainers 1 and 1^a in Fig. 1 in the drawing to take tools of varying sizes and types. By positioning the angular apertures 4 and 4^a shown in 100 Fig. 1 at opposite angles, the tendency of the die block to travel with the punch is prevented and the tendency of the punch to remain in the die block is also prevented by the retainers here shown; the movement of the 105 punch toward the die block or die block toward the punch being prevented by the wedging engagement of the ball 5 or 5^a between the wall of the angular aperture and the wall of the arcuate groove in the tool. 110

From the foregoing description it becomes evident that the device is of a simple nature and accomplishes the objects desired and by the mechanism here shown the punch head 115 is held in position to exactly engage the aperture in the die block and thus a device is provided which is very efficient and exact in operation and which will not easily get out of order.

Having thus briefly described our invention, its utility and mode of operation, what we claim and desire to secure by Letters Patent of the United States is—

1. In a retainer for punches, dies and similar tools, a base, a supporting member 125 removably secured thereto and having a central aperture, a tool retainer held in position by the supporting member, the tool retainer having a central aperture, a spring-pressed ball supported by the retainer and normally 130

extending into the aperture therein, the tool being adapted to fit in the aperture and seat against the base and having an arcuate groove of a radius greater than the radius 5 of the ball in the face thereof in which the ball may engage to bind the tool in position.

2. In a retainer for punches, dies and similar tools, a base, a centrally apertured 10 retainer detachably secured to the base, the retainer also having an angular aperture opening thereinto, a spring-pressed ball in the said angular aperture, and a tool having a shank provided with an arcuate groove of 15 a radius greater than the radius of the ball in the side thereof engaged by the ball when the shank is seated against the base in the said aperture of the retainer.

3. In a retainer for punches, dies and 20 similar tools, a base, a centrally apertured retainer removably secured to the base, the tool having a shank adapted for insertion in the aperture of the retainer, the retainer also having an aperture in the wall thereof extending 25 at an angle to the longitudinal axis of the central aperture and opening thereinto, there also being an opening in the retainer extending from the angular aperture through the face of the retainer, a ball fitting 30 within the angular aperture, a spring forcing the ball to extend partially into the central aperture of the retainer, a recess formed in the surface of the tool shank having a face at an angle to the axis of the tool against 35 which the ball engages when the shank is seated against the base, the aperture extending through the face of the retainer into engagement with the base permitting insertion of an instrument to withdraw the ball from 40 engagement with the tool.

4. In a retainer for punches, dies and similar tools, a base, a supporting member having a central circular aperture counter-bored at the inner end adjacent the base, 45 means for detachably securing the support-

ing member on the base, a retainer having a portion engaging in the enlarged part of the supporting member and fitting the aperture of the supporting member, said retainer having a central aperture and an 50 aperture at an angle thereto opening into the central aperture, a spring-pressed ball in the angular aperture, and a tool having a notch formed in the face thereof engaged by the ball when the tool is positioned in the 55 central aperture of the retainer and seated against the base.

5. In a tool retainer, a base, a centrally apertured retainer detachably secured to the base, the retainer also having an angular 60 aperture opening into the central aperture, a spring-pressed ball in the said angular aperture and a tool having a shank adapted for insertion in the central aperture to engage the base, said shank having an arcuate 65 groove on one side only, said groove being arcuate in form both longitudinally and transversely of the axis of the shank, the groove transversely of the shank being at its deepest part substantially of the same radius as the ball and longitudinally being formed on an arc of a radius greater than 70 the radius of the ball.

6. In a retainer for punches, dies and similar tools, a base, a centrally apertured 75 retainer secured to the base, the tool having a shank adapted for insertion in said aperture, the retainer also having an aperture in the wall thereof extending at an angle to the longitudinal axis and opening into 80 the central aperture, a spring-pressed ball in said aperture, and a tool having a shank provided with an arcuate groove in one side thereof of a radius greater than the radius of the ball in which the said ball engages. 85

In testimony whereof we sign this specification.
